SCALE INHIBITOR FOR PIPELINES

Arthur N. Wells, Belmont, Calif.

Application October 1, 1953, Serial No. 27,046

Term of patent 14 years

(Cl. D91—3)

Fig. 1.

Fig. 2.

To all whom it may concern:

Be it known that I, Arthur N. Wells, a citizen of the United States, and a resident of the city of Belmont, State of California, have invented a new, original, and ornamental Designs for a Scale Inhibitor for Pipelines, of which the following is a specification, reference being had to the accompanying drawing, forming a part hereof.

Fig. 1 is a perspective view showing one end and one side of a scale inhibitor for pipelines embodying my new design; and

Fig. 2 is a view of the other side thereof.

I claim:

The ornamental design for a scale inhibitor for pipelines, as shown.
